UNITED STATES PATENT OFFICE.

JACOB DAVIS, OF NEW YORK, N. Y.

DESIGN FOR A RULE OR MEASURING-STICK.

SPECIFICATION forming part of Design No. 25,609, dated June 9, 1896.

Application filed December 10, 1895. Serial No. 571,713. Term of patent 7 years.

To all whom it may concern:

Be it known that I, JACOB DAVIS, a citizen of the United States, and a resident of New York, in the county of New York and State of New York, have invented and produced a new and original Design for a Rule or Measuring-Stick, of which the following is a specification, reference being had to the accompanying drawing, forming part thereof, in which the figure represents the form and configuration of my design.

The leading feature of my design consists in the form and outline of my new and original design for measuring-sticks or rules, as shown in the accompanying drawing, which illustrates my design with relation to configuration and form, only free from the figures, words, and characters which I use in practice, and this feature shows a measuring-stick or rule one edge of which is formed practically similar to an ogee curve, the ends being slightly beveled, and the opposite side of the stick, adjacent to the beveled end, is practically straight, the remaining portion being segmental or curved, the curve extending to the opposite or straight end of the

stick or rule. This particular form and configuration and outline of the stick or rule constitutes the leading feature of my design and is the most essential feature thereof. 30

The rule or measuring-stick made according to my new and original design may be of any desired width and thickness and formed of any desired size, and in practice figures and letters are formed thereon designed to 35 represent or designate the various measurements employed in cutting a pattern for a dress or any part thereof.

Having fully described my new and original design, what I claim, and desire to secure by 40 Letters Patent, is—

The new and original design for a measuring-stick or rule substantially as herein shown and described.

In testimony that I claim the foregoing as 45 my invention I have signed my name, in presence of the subscribing witnesses, this 6th day of December, 1895.

JACOB DAVIS.
